UNITED STATES PATENT OFFICE.

ASHLEY GUY OGDEN, OF BALTIMORE, MARYLAND.

PRINTING DEVICE.

1,172,386.

Specification of Letters Patent. Patented Feb. 22, 1916.

Application filed July 23, 1914, Serial No. 852,641. Renewed July 10, 1915. Serial No. 39,175.

To all whom it may concern:

Be it known that I, ASHLEY G. OGDEN, a citizen of the United States, and a resident of Baltimore, in the State of Maryland, have made certain new and useful Improvements in Printing Devices, of which the following is a specification.

My invention relates to improvements in printing devices, especially those devices wherein a number of prints are to be made from a single negative, and it consists in the combinations, constructions and arrangements herein described and claimed.

An object of my invention is to provide improvements whereby a multiplicity of prints may be made on a sensitized plate in a minimum of time.

A further object of my invention is to provide a device of the type described in which the prints are made in such a manner that the designs are accurately spaced in symmetrical relation so that when the designs are etched and are transferred to a plate or sheet the latter may be cut or punched accurately.

A further object of my invention is to provide a device by means of which a single negative may be moved from position to another over the sensitized plate while the remainder of the plate may be covered to prevent double exposure.

Other objects and advantages will appear in the following specification, and the novel features of the device will be particularly pointed out in the appended claims.

My invention is illustrated in the accompanying drawings forming part of this application in which, Figure 1 is a plan view of the device, certain of the screens being removed, Fig. 2 is a section along the line 2—2 of Fig. 1, Fig. 3 is a section along the line 3—3 of Fig. 1, Fig. 4 is a section along the line 4—4 of Fig. 1, Fig. 5 is a perspective view of a portion of the device certain parts being shown in section, Fig. 6 is a partial plan view of a modified form of the device, Fig. 7 is a section along the line 7—7 of Fig. 6, Fig. 8 is a perspective view of a portion of the device shown in Fig. 6, Fig. 9 is a perspective view of a portion of a modified form of the device, Fig. 10 is a plan view of another modified form, Fig. 11 is a section along the line 11—11 of Fig. 10, Fig. 12 is a perspective view of a portion of the device shown in Fig. 10, and Fig. 13 is a view similar to

Fig. 12 showing a modified form of the device.

In carrying out my invention I provide a frame consisting of the outer members 1 having an inwardly extending flange 1^x. Disposed on the flange 1^x is plate of glass 2. This plate carries strips 3 of wood or other suitable material which may be set into grooves in the glass, as shown in Fig. 3, or may be otherwise suitably secured to the glass plate.

As will be seen from Fig. 5, the strips 3 are preferably beveled on their inner edges, and may be provided with a scale 4. The strips 3 are recessed to provide run ways for the negative 5 and for screens 6, see Fig. 1. In this figure the screens have been removed from the left hand portion of the figure, but it will be understood that both halves of the device are alike and in fact only one-half of the device shown in Fig. 1 might be used, since it constitutes in itself a complete printing device.

In order to provide for an easy movement of the negative 5 and the screens 6, I may line the run-way with a U-shaped metallic lining 7 and may cover the edges of the negative 5 with a U-shaped metallic covering 8, see Fig. 3, so that metal will slide against metal.

In Figs. 12 and 13 I have shown modifications of the means by which sliding movement of the negative may be readily accomplished. In Fig. 12 the strip 3 is recessed to receive a solid insert 7^x provided with a groove arranged to receive a tongue 8^x of an edge strip carried by the negative 5. In Fig. 13 the strip 3 has a member 7^w having a tongue arranged to enter the groove in the member 8^w carried by the plate 5.

At the corners of the frame I provide tapering bores 2^x in the glass plate 2, see Fig. 2, and in these bores I insert tapered stop pins 9. The tapered portion of the stop pins is square in cross section so as to prevent the turning of the pin, while each pin has a cut-away corner 9^a, this corner facing the center of the frame. At intervals along the strips 3 I provide threaded openings 10 for the reception of set screws 11 which when tightened will cause the negative 5 to remain securely in its shifted position.

From the foregoing description of the various parts of the device the operation thereof may be readily understood.

As stated before, the printing mechanism

is primarily designed for printing, upon a sensitized metallic plate, a large number of designs, which will be symmetrically and accurately spaced apart upon the plate, when the printing process has been completed. The metal plate may then be etched and used as a plate from which to print the designs upon other sheets of metal which can then be stamped out with a die. Thus, no printed caps for bottles, identification tags or other similar articles may be made.

In order to give a good idea of the manner in which the printing frame is operated I will state the complete process, although it will be understood that other means of making the negative might be used than that described herein. A design is first made, and this may be an india ink drawing on white card board. A photograph is now taken of this design, and prints or proofs of the photograph are made. These proofs are then pasted or otherwise secured to a suitable backing in the relative positions in which the designs are to finally appear. This is done by marking off the positions of the proofs accurately before hand. A photograph is now taken of the proofs, and the negative of this photograph is the negative 5 heretofore mentioned.

The negative 5 as will be observed, is of such length as to accurately fit between the members 3. This negative lies flat upon the glass plate 2. Opaque screens 6 of precisely the same width as the negative 5 are provided, and the ends of the screens 6 are also adapted to run in the run-ways provided for the negative 5. In order that there may be no lines of light across the plate I preferably bevel the edges of the negative and of the screens at an angle of 30°, as shown in Fig. 4.

In making the first row of prints the two pins 9, for instance, at the top of Fig. 1, are removed and the screens (numbering four in the present instance) placed in the run ways and are pushed until the first screen comes into contact with the pins 9 at the lower portion of Fig. 1. The negative 5 is now placed in the run way and pushed in as far as it will go, after which the upper pins 9 are replaced. The sensitive plate 12 is now placed in position against the negative, the corners of the plate entering the cut away portions 8 of the pins 9 so as to hold the plate in position. A print is now taken in any suitable manner. The opaque members 6 prevent exposure to the unexposed portions. After exposure the pins 9 are all removed and the outer opaque plate or slide is removed and placed in at the opposite side against the negative which is moved forward. The lower pins are replaced and both the negative and opaque slides are pushed forward as far as they will go, the pins are replaced and the metallic plate is

again placed in position. This brings the negative to its second position, and in view of the fact that the negative as well as the opaque plates are accurately ground the second position of the negative will permit a print to be made which will bear the same relation with the print just previously made as the designs of the negative itself. These steps are repeated until every portion of the sensitized plate has been printed. The latter may now be removed and etched and all the designs on the etched plate will be symmetrically disposed so that when the etched plate is used for a printing medium a large number of designs may be transferred. These designs will be accurately and equally spaced apart. In order to prevent the shifting of the negative I make use of the set screws 11.

In Fig. 10 I have shown a modified form of the device in which rollers 13 are journaled in the frame members 1 and are provided with handles 14 by means of which they may be rotated. These rollers carry flexible curtains 15. The glass plate 2 is recessed at 2° in order to allow room for the curtains. The curtains 15 are attached to a rectangular frame 16 which is of such size as will just receive the negative 5. As will be seen in Fig. 11 the frame 16 and the negative 5 are of the same thickness so that when the negative is placed in the frame it will lie flat on the glass plate 2. In this form of the device a print is made on the sensitized metal plate, not shown, but which is designed to be placed immediately above the negative. One of the rollers is now turned so as to move the frame 16 and the negative 5 to its second position which may be indicated by the scale. Another print is taken and these steps are repeated until the entire plate has been traversed by the negative and the desired number of prints have been taken.

In Fig. 6 I have shown a further modification in which the strips 3 are recessed along their inner edges to provide a run way for a U-shaped strip 17, see Fig. 8. Extending transversely of the device are two bars 18 and 19 whose ends have tongues 118 arranged to enter the member 17. The latter is provided with threaded openings 20, arranged to receive set screws so as to space the members 18 and 19 accurately apart and to hold them in spaced relation.

In this instance the negative 5 consists of a small plate of glass having a single design and being provided with tongued strips 21, see Fig. 7, which slide in grooves in the members 18 and 19. In using this form of the device the negative 5 is placed at one side and a print is taken. The remaining portion of the plate may be screened by curtains such as those described in connection with Fig. 10, while the ex-

posed portions of the plate between the strips 18 and 19 may be covered with opaque paper or other similar material. The negative is moved transversely of the frame and prints are taken in succession. When a row has been made the negative is shifted longitudinally of the frame and another row is printed.

Instead of shifting the members 18 and 19 by hand it may be done by means of a screw mechanism such as that shown at 22 in Fig. 9. This screw as will be observed passes through a member 17^a similar to the member 17 in Fig. 8. The screw is provided with a handle 23 and by turning this handle the frame members 18 and 19 bearing the negative 5^a may be shifted at will over the plate 2.

I claim:

1. In a printing device, a frame, a glass plate carried by said frame, removable stop members carried by the glass plate for holding a sensitized plate in position, a negative slidably disposed on said frame and movable therealong to cover portions of the frame.

2. In a printing device, a frame, a glass plate carried by said frame, removable stop members carried by the glass plate for holding a sensitized plate in position, a negative slidably disposed on said frame and movable therealong to cover portions of the frame, and means for covering the exposed portions of the plate not covered by the negative.

3. In a printing device, a frame, a glass plate carried by said frame, removable stop members carried by the glass plate for hold-

ing a sensitized plate in position, a negative slidably disposed on said frame and movable therealong to cover portions of the frame, and means for covering the exposed portions of the plate not covered by the negative, said last-named means comprising a series of opaque slides of same width as the negative.

4. In a printing device, the combination with a negative, of a frame having a pair of parallel grooved guide members, the ends of said negative being arranged to slide in the grooves in said guide members, a glass plate disposed on one side of the negative and in close engagement therewith, and a plurality of opaque slides of the same width as the negative and arranged to cover the portions of the glass plate not covered by the negative.

5. In a printing device, the combination with a negative, of a frame having a pair of parallel grooved guide members, the ends of said negative being arranged to slide in the grooves in said guide members, a glass plate disposed on one side of the negative and in close engagement therewith, a plurality of opaque slides of the same width as the negative and arranged to cover the portions of the glass plate not covered by the negative, a series of removable stop members carried by said glass plate and having cut away portions arranged to receive the corners of a sensitized plate for holding the latter in position.

ASHLEY GUY OGDEN.
